TWISTER RING AND TRAVELER

Aston Dennis Granger, Long Eaton, England, assignor to A. D. Granger Limited, Long Eaton, England

Application September 27, 1933, Serial No. 691,233
In Great Britain September 28, 1932

2 Claims. (Cl. 118—59)

This invention is for improvements in yarn doubling machines and more particularly relates to the lubrication of the rings of yarn doubling and like machines of the kind in which the yarn, 5 in its passage to the bobbin, is controlled by a yarn guiding traveller which runs around a ring surrounding the bobbin and which ring receives rising and falling motion so as to lay the yarn evenly on the bobbin. It has for an object to provide lubricating means which can be applied to existing machines without necessitating alterations to the rail or plate in which the rings are 10 located.

A further object of the invention is to provide 15 lubricating means whereby an even and adequate supply of lubricant is supplied to the interior of the rings while they are running, which supply ceases automatically when the rings are not running, and restarts automatically when they are 20 started.

As is well known, in yarn doubling machines of the kind referred to, the rings upon which the 25 yarn guiding travellers run are disposed in openings provided for them in a longitudinal rail or in openings in plates secured to such a rail, and they project both above and below the rail or plate so that the travellers (which are made of wire) can be formed with parts to engage with the outer sides of both of the upper and lower 30 edges of the rings and be thus retained thereon. In the majority of existing machines, it is necessary for the operator at frequent intervals to apply a little lubricant to the traveller rings and, as this operation can only be effected when 35 the ring to be lubricated is not working, the output of the machine is thereby materially reduced. In such spasmodic lubrication it frequently occurs, moreover, that an excess of lubricant is applied which gets onto the yarn. These are disadvantages which are obviated by the present 40 invention.

In order that the said invention may be better understood, reference will now be made to the 45 accompanying drawing which shows the relevant parts of a yarn doubling machine. In this drawing,

Figure 1 is a vertical cross section through the 50 ring and associated parts provided according to this invention,

Figure 2 is a plan illustrating the invention as applied to a traveller ring mounted in a plate, while

Figure 3 is a plan showing the invention applied 55 to traveller rings mounted in a rail,

Throughout this description like reference numerals indicate like parts.

In the construction shown in Figures 1 and 2, the traveller ring 10 is mounted upon a ring-holding plate 11, it being understood that a plurality of such plates would be attached to a rail to which rising and falling motion is imparted. A wire traveller 12, through which the 5 yarn is threaded, revolves in a circle upon the ring and an object of the invention is to supply 10 lubricant to this traveller in quantities which are adequate but are not sufficiently large to get on to the yarn. To this end, there is a small oil container or reservoir 13 secured to the ring-holding plate 11 a short distance from the 15 external periphery of the ring 10. From this reservoir the lubricant is supplied by means of a short tube 14, just above the level of the plate 11, which tube fits into the ring and terminates in a small duct 15 at the inner periphery of the ring. 20 This duct is preferably of such a size (carefully chosen with regard to the viscosity of the oil employed, or vice versa) that the lubricant does not flow freely through it but merely protrudes from the end thereof in part-spherical or meniscus 25 form and is wiped off by the traveller 12 at each passage of the latter. As the traveller wipes off the protruding globule of oil, the molecular adhesion of the oil and the slight suction action 30 set up by the traveller ensures that the supply will be automatically maintained and that there will be no excess. As a consequence of this arrangement, the supply of oil to the traveller 12 and to the ring 10 upon which it runs is not only regular and well balanced but ceases as soon as the 35 machine stops so that there is no waste, whilst the supply is renewed when the machine is restarted.

The distribution of the oil removed from the 40 end of the metering duct 15, and the automatic recommencement of lubrication after a stoppage, is materially facilitated by the provision of an 45 annular groove 16 in the interior periphery of the ring. It will be understood that this groove conducts the oil all round the inside of the ring, and when the machine is brought to a standstill a certain amount of oil remains in the said groove which residue, when the machine is restarted, enhances that suction or drag upon the lubricant 50 in the tube 14 and in the reservoir which ensures what may be termed the self-priming action in the lubricating system. Preferably the upper edge 16a of this groove is chamfered so as to lead the lubricant down into it, while the lower edge 16b is squared so as to retain the lubricant therein. 55

Doubling machines are required to deal with fluffy material such as cotton, but it will be appreciated that the presence of fluff in the lubricating system will rapidly lead to a break down 5 thereof, for example by choking the tube 14. Therefore the container or reservoir 13 is preferably provided with a lid 17, in which there is a filling aperture 18. This aperture is normally closed by means of a displaceable cover 19 in 10 which, or in the lid 17, there may if necessary be a very small air inlet, such as is indicated at 20.

The filling aperture 18 is preferably arranged to permit of grease gun being applied thereto to fill the container with oil. Such a gun may be 15 applied thereto at any time in order to force the oil up to the point of delivery in the interior of the ring, so that there is a small quantity of lubricant protruding from the duct, and to remove any obstructions in the restricted oil 20 passage.

If so desired, the arrangement described hereinbefore with reference to Figures 1 and 2 may be duplicated and the oil fed to each ring at two opposite points from two independent oil containers, but in the majority of cases, it will be 25 found that the supply of viscous oil at one point in the ring will be adequate to lubricate the ring and traveller. If it is desired to feed the oil to two points in each ring, then the oil may be so fed 30 from a single container by forming the ring 10 with two ducts 15 and connecting both to a single container such as is shown at 13.

When the traveller rings 10 as hereinbefore described are each disposed in an independent plate 35 11, it will readily be appreciated that a container 13 must be provided for each ring, but when the rings are disposed in openings in a rail, this is not necessary for one container may be employed to supply oil to a plurality of rings.

40 A convenient arrangement which may be adopted in such a construction is shown in Figure 3. In this figure there is a single container 13' in conjunction with each pair of rings 10', said container being mounted upon the rail 21, in 45 which the rings are disposed, in the space between the two rings which it is to supply with lubricant. The ducts 15' in the rings, details of which are as hereinbefore described with reference to Figures 1 and 2, are so disposed that they can both 50 be connected to the common container 13' by short straight tubes 14', which as shown converge from the rings to the container. In such an arrangement, the number of oil containers required

is reduced by one half and a further advantage is that the common container 13' is held in position by the two supply tubes 14'.

By the means hereinbefore described, an adequate and constant supply of lubricant is supplied to the travellers, and it will readily be appreciated that the lubrication system provided by this invention has this advantage over the hand lubrication hitherto commonly employed, and over such lubrication systems as have been hitherto proposed, that at no time is an excess of lubricant, sufficient to foul the yarn, supplied and that the even supply terminates when the ring is brought to a standstill and recommences automatically when the ring is brought into operation. Moreover, as the system is totally enclosed, the trouble usually experienced owing to fluff from the yarn getting into the oil is entirely obviated and hence this system can be employed with perfect safety and reliability in machines for 20 doubling cotton and other fluffy yarns.

I claim:

1. In a yarn doubling or like machine, a ring for supporting and guiding a traveller, which ring has formed in its interior face an annular groove, 25 a closed reservoir for a viscous lubricant, a gravity feed conduit extending from the reservoir and terminating in the said groove in the ring, and being at its end of a meniscus-forming size, and a traveller moving around the ring in close 30 proximity to the said groove and arranged to wipe off the protruding lubricant as it passes the meniscus-forming orifice thereof.

2. In a yarn doubling or like machine, a ring rail, a ring supported therein for guiding a tray- 35 eller, which ring is formed on its inner face with a shallow annular groove and is drilled in said groove with a metering orifice of meniscus-forming size, a closed reservoir for lubricants sup- 40 ported on the rail, a conduit tube extending about the rail from the reservoir to the metering orifice in the ring adapted to convey lubricant to such orifice and a traveller movable about the ring in close proximity to the groove and operating to 45 wipe off the lubricant protruding from the meter- 50 ing orifice for lubricating purposes, allowing the immediate protrusion of another portion of lubricant, the metering orifice serving to prevent flow of lubricant when the machine is at rest and the traveller not operating.

ASTON DENNIS GRANGER.
